UNITED STATES PATENT OFFICE.

WILLIAM H. STIEFEL, OF ANGOLA, INDIANA.

COAL SAVER.

Application filed October 17, 1923. Serial No. 669,116.

To all whom it may concern:

Be it known that I, WILLIAM H. STIEFEL, a citizen of the United States, and a resident of Angola, in the county of Steuben and 5 State of Indiana, have invented certain new and useful Improvements in Coal Savers, of which the following is a specification.

This invention relates to a composition of matter for aiding in a more complete combustion of coal.

An object of the invention is the provision of a composition of matter which when employed as an aid in the combustion of coal will not only provide for an economy 15 in the coal but produce brighter and hotter fires and likewise eliminate clinkers and soot.

A further object of the invention is the provision of a composition of matter which 20 will cause a complete combustion of the coal by supplying the necessary elements to cause consumption of the soot and smoke.

In carrying out my invention, I prepare the composition of matter in small quantities such as five pounds of common salt, 25 three ounces of oxalic acid and sufficient lamp black to color the composition black. The ingredients are thoroughly mixed and placed in air-tight containers for distribution to the public.

When it is desired to use the same for aiding in the combustion of coal, the contents of the package, which contains the ingredients in the proportions noted above, is 35 dissolved in fifty gallons of water and this is sufficient to spray two tons of coal. It must be borne in mind that the coal should be sprayed just before placing the same in the furnace in order to obtain the best results.

In the ordinary consumption of coal, a

great deal of soot and black smoke are produced and carried through the flues with some of it being lost in the atmosphere while the remainder collects upon the sides of the 45 furnace walls and upon the flue pipes. The soot and black smoke are unconsumed carbon and form the best heat units of the coal and thereby by lack of proper combustion these heat units are lost in the consumption 50 of the coal. The soot collecting upon the interior walls of the furnace tends to insulate such walls against the passage of heat and this is particularly true in the boilers 55 of hot water furnaces and in which the soot covered boiler pipes do not receive the maximum of heat.

In the use of my composition of matter the soot is entirely consumed, materially raising the heating value of the coal. 60

By employing salt in the mixture a cleaner hotter and more snappy fire is had. Oxalic acid aids in the consumption of the soot either singly or in combination with the salt when dissolved in water. It has the 65 effect of causing the coal to burn more slowly but at the same time, since it aids in the combustion of gases which are ordinarily lost through the chimneys, a more intense fire is produced. 70

What I claim is:

1. A composition of matter comprising five pounds of common salt, three ounces of oxalic acid and lamp black sufficient to color the composition black. 75

2. A composition of matter comprising five pounds of common salt, three ounces oxalic acid, sufficient lamp black to color the mixture of salt and oxalic acid black, and fifty gallons of water.

WILLIAM H. STIEFEL.
